UNITED STATES PATENT OFFICE.

HOWARD V. HILL, OF READING, PENNSYLVANIA, ASSIGNOR TO CURTIS & JONES CO.,
OF READING, PENNSYLVANIA, A CORPORATION OF PENNSYLVANIA.

HEEL-COMPRESSING MACHINE.

Specification of Letters Patent.

Patented Feb. 2, 1915.

1,127,001.

Application filed September 16, 1914. Serial No. 361,929.

To all whom it may concern:

Be it known that I, HOWARD V. HILL, a citizen of the United States, residing at Reading, State of Pennsylvania, have invented a certain new and useful Heel-Compressing Machine, of which the following is a specification.

This invention is a heel compressing machine wherein the operations of feeding the 10 unfinished heels, compressing said heels, and discharging the compressed heels are performed expeditiously and automatically. In this art it is customary to employ a machine wherein the mold or die is carried by a vertically movable head, and the incomplete 15 heels are supplied automatically by a feed mechanism of one form or another to said die or mold.

One part of my invention pertains to a 20 simple and effective heel-feed mechanism operable by the rise and fall of the head. Such mechanism embodies a guide member fixed to the head so as to rise and fall therewith, a reciprocating feed slide movable relative to the guide member and operable to advance the incomplete heel into the die or mold, a drop weight connected with said feed slide for imparting movement in one direction thereto, a rotatable member such 25 as a pulley mounted on the head or mold, a chain or the like coiled on the rotatable member and attached to the feed slide for pulling it in a direction contrary to the drop weight, and a second chain or the like 30 coiled in an opposite direction on the rotatable member and secured in a fixed part of the machine so that as the head descends this last named chain will turn the pulley and thus act on the other chain to draw the 35 feed slide inwardly toward the die for feeding the heel automatically thereto.

Another part of my invention consists in means for positively operating the pressure member or plate which is positioned within 40 the die or mold and is adapted, in the rise of the head, to be brought into co-operative relation to another pressure member supported in a fixed position above the mold or die, and in alignment vertically therewith. Said 45 positively operating means is a cam positioned within a slot provided in a rest block below the mold or die, with which cam contacts the lower end of a stem on the lower pressure member. Said cam is carried by a 50 shaft journaled in the rest block, and to this 55 shaft

shaft is secured a rotatable member, the latter being preferably in the form of a double pulley. Around the respective parts of this pulley are oppositely wound two chains, one 60 extending upwardly and the other downwardly, the upper end of one chain being anchored fixedly on the machine head and the lower end of the other chain being similarly anchored in the machine frame, where- 65 by upon the rise and fall of the die-carrying head the two chains so operate the double pulley as to rotate the shaft and the cam to impart the required movement to the pres- 70 sure member within the die or mold for the purpose of receiving a fresh heel, compress- 75 ing it, and of moving the compressed heel to such position that it will be ejected by the incoming heel.

Other features and advantages of my in- 75 vention will appear in the course of the fol- 80 lowing detailed description.

In the drawings, Figure 1 is a side eleva- 85 tion of a heel compressing machine embody- 90 ing my invention. Fig. 2 is an elevation viewed from that side of the machine into 95 which the heels are introduced into the die or mold. Fig. 3 is a sectional plan view, the plane of the section being indicated by the line 3—3 of Fig. 1. Fig. 4 is a side eleva- 100 tion, on an enlarged scale, illustrating the feed mechanism for the mold or die. Fig. 5 is a vertical section through the mold illus- 105 trating the co-operating pressure members and the cam mechanism for operating that pressure member which is positioned within 110 said mold. Fig. 6 is a sectional plan view of the distance block imposed upon the rest block, the plane of the section being indicated by the dotted line 6—6 of Fig. 5. Figs. 7 and 8 are detail perspectives of the 115 upper pressure member and the lower pres- 120 sure member, respectively. Fig. 9 is a detail section through the rest block to show the cam. Fig. 10 is a detail perspective view of the heel prior to compressing. Fig. 11 is a cross section through the feed slide on the 125 line 11—11 of Fig. 3.

Referring to the drawings, A is the usual frame provided with the usual guides for the vertically movable head B, said frame 130 being provided, also, with the fixed head- 135 block C and with suitable bearings for the drive shaft D, countershaft D' and crank- 140 shaft D². To the head B is pivoted one member E of a toggle, the other member E' 145

of which is pivoted to frame A, said toggle being operated as usual by the crankshaft, whereby reciprocating motion is imparted to said head B. Said movable head B carries the mold or die F, the feed mechanism, and the several parts associated therewith.

In contradistinction to some prior machines, the mold F of my machine is a solid block of metal with no moving parts. The mold block is provided with a mold cavity *f* the shape of which conforms to the shape of the heel and the dimensions of which mold cavity are only slightly greater than the dimensions of said heel in order that the heel when compressed will conform to the die and said heel may enter and leave the die freely. The mold cavity opens at top and bottom through the corresponding faces of the mold, but said mold is imposed upon a distance block G so that the under side of the mold cavity is closed by the distance block. The mold and the distance block are secured solidly together in any suitable manner, and said distance block is attached 25 removably to a rest-block H, for which purpose the distance block is provided with a plate or flange *g* adapted to be fastened by screws or bolts *g'* to the rest block. As is usual in machines of this character, the rest block H, has an inclined lower face contacting with an oppositely inclined face on a base block H' carried by the head B, so that a relative movement between blocks H H' can be secured by the adjustment of a screw 30 H², shown in Fig. 4.

It will be noted that the mold is imposed upon the distance block, and the latter in turn imposed upon the rest block; and, further, that the mold, and distance block are removable by taking out the screws *g'* thus enabling other molds to be positioned upon the rest block, whereby a number of molds may be used interchangeably in the machine. The distance block is provided with a vertical aperture *h* which opens into the mold cavity *f*, in Fig. 5, whereas the rest block is provided with a vertical slot *h'*, the latter being in alignment vertically with said slot *h*.

Within the slot of the rest block is positioned a cam I, see Figs. 5 and 9, said cam being shown as having the high part *i* and the low part *i'*. The cam is carried by a horizontal cam-shaft I', journaled in the rest block and extending beyond one side thereof, see Fig. 5, and this cam shaft is operated by the rise and fall of the head B so as to impart rotative movement automatically to the cam.

The preferred means for operating the cam shaft consists of a double pulley J and cords, chains or other flexible connections, J', J². The double pulley is secured fast to the protruding end portion of the cam shaft, and the chains J' J² are wound or

coiled in reverse directions around the respective members or parts of said pulley, said chain J' extending upwardly and anchored at a fixed point, as by the I bolt *j* attached to the head block C, whereas the other chain J² extends downwardly from the pulley in order that the lower end thereof may be similarly anchored at a fixed point, as by the I-bolt J', see Fig. 1 and 2. It will be understood that upon the descent of head B and the parts movable therewith, the chain J' will be uncoiled from pulley J, thus rotating the latter and winding chain J² thereon, the shaft I' and cam I being thus given rotative movement in one direction; whereas upon the ascent of head B the reverse operations take place, i.e. chain J² is uncoiled from pulley J, the effect of which is to wind chain J' on said pulley and to impart rotative movement to the shaft and the cam in an opposite direction.

K designates the pressure member which is positioned and operates within the mold cavity, and L is the relatively stationary pressure member which is supported in a fixed position on the under side of head C so as to occupy a co-operative relation to member K and the mold when the heel is under compression. The pressure members K L conform, substantially, to the shape and dimensions of the heel to be compressed between the opposing surfaces of said members. As shown, member L is attached to or formed with a shank, l, dovetailed in cross section, and detachably mounted in a guide, l', provided on the under side of the head C. If desired, liners (not shown) may be employed in connection with said pressure members, or either of them, to regulate the pressure upon the heel, it being preferred to use one or more liners in connection with the fixed pressure member L.

The pressure member K is provided with a depending stem k, the latter being shown as partly cut away on the respective sides in Fig. 8, said stem extending downwardly from the die through the vertical aperture *h* in the distance block and into the slot *h'* of the rest block, whereby the lower extremity of the stem is in contact with the peripheral portion of cam I. The rotation of the cam determines the position of the lower pressure member within the cavity of the mold, and said cam thus operates to impart movement to the pressure member so that the latter will co-operate with the upper pressure member L and it will position the compressed heel substantially flush with the top surface of the mold in order that the incoming heel, fed by the feed slide, will operate to eject the compressed heel into a discharge chute M. Said chute is shown as occupying an inclined position at the rear of the machine, the inlet of which chute is 130

adjacent the top face of the mold, at the rear thereof see Figs. 1 and 4, so that the compressed heels ejected from the mold will pass directly into the chute.

I will now describe the feed mechanism for supplying the heels to the mold or die, one of said heels prior to compression being shown at X in Fig. 10, by reference to which it will be noted that it embodies a plurality of layers each of which is cut to the desired form and size, said layers being assembled in matching relation and superposed, suitable means being employed for uniting the layers, as by cementing them or by mechanically fastening them through the medium of a tack. Said feed mechanism includes, as one element thereof, a slide O, provided on its under side with a rib o, said slide resting upon a supporting guide way P, herein shown as a horizontal plate occupying a fixed relation to the mold F so as to rise and fall therewith. The plate P extends outwardly from the mold, and said plate is held in fixed relation to said mold by the angle bars Q and by a brace bar Q', the latter being inclined to the guide plate P, see Fig. 4 so that the brace bar is secured at one end to the rest block H and at the other end to the guide plate P. Said guide plate is shown as provided with a longitudinal slot p, in which is fitted the rib o of the feed slide O, the latter being thus connected with the guide plate so as to be directed or limited to movement in a rectilinear path. The angle bars Q each comprise a piece of metal, of angle shape in cross section, said bars being parallel to each other and positioned upon the guide plate P to extend therefrom over the mold F, at the respective sides of the cavity f therein. These bars Q are secured firmly to the guide plate P by screws q, and at their free ends they are fastened by screws q' to the top of the die. The slide O travels between the opposing edges of the guide bars, and when the slide is drawn forward the operator should deposit an unpressed heel between the bars Q and against the edge of said slide O, see Fig. 3, whereby the movement of the slide toward the mold acts upon the heel to shove it over the plate P and between the bars Q so as to feed the heel accurately into position over the mold cavity, whereby the heel is directed to rest upon the pressure member K in the operation of the compressing mechanism.

The feed slide is operated automatically by mechanism dependent upon the rise and fall of the head B, and to this end I have provided a double pulley S, the latter being mounted for idle rotation on a stub shaft or arbor s, secured to the rest block H, see Fig. 5. On this pulley is coiled or wound two chains T, T', the chain T being coiled in one direction on one part of the pulley and ex-

tending upwardly to the fixed head so as to be anchored by an eye bolt t, see Fig. 2, whereas the other chain T' is coiled in a reverse direction to chain T and on the other member of the pulley, said chain T' extending forwardly to the front end of slide O, whereby said chain T' can be attached to a stud t' of the slide. The chains and the pulley coöperate in imparting movement in one direction to the feed slide, but the movement of the slide in an opposite direction is effected by a drop weight U, to which a cord or chain u is attached, the latter extending over a pulley u' mounted upon the outer end of fixed plate P and said cord or chain being fastened to the outer end of feed slide O at x.

The operation is as follows: A heel having been previously positioned on the pressure block K, the upward movement of head B operates through chain J² to turn shaft I' and cam I so as to lower block K and the heel therein within the mold, and as the head B and mold reach the limit of their upward travel, the heel is compressed between within the mold and between the co-operating pressure blocks K L. At this time, the feed slide O is drawn outward by the drop weight. Upon the descent of the head the mold and the other parts, the cam I acts on the stem of the block K to retain the compressed heel in a raised position substantially flush with the top surface of the mold. At this time, the attendant places an unpressed heel on the plate P and in the rear of the slide O, whereupon the chain T and pulley S act to pull on chain T' and draw the slide O rearwardly against the pull of weight V, as a result of which the unpressed heel is forced by the slide O between the guide bars Q so that the pressed heel will be forced off the block K, and away from the mold, into the chute M and simultaneously therewith the unpressed heel, advanced by the feed slide O, will take position on the pressure block K, the incoming heel contacting with the compressed heel and operating to displace it as described. The head now rises and the cam lowers the heel into the mold so as to compress it as described, the feed slide in the meanwhile being drawn outwardly by the drop weight, so as to continue the operations of pressing the heel and to therefore feed an unpressed heel to the mold in a manner to eject the compressed heel.

Having now described my invention, what I claim as new is:—

1. In a heel compressing machine, the combination with a reciprocating head, and a mold thereon, of a pressure member positioned within the mold, a cam shaft movable with said head, a rotative cam carried by said shaft for directly actuating the pressure member so as to impart movement

- thereto relative to the mold, a pulley carried by the cam shaft, and operating cables coiled oppositely to each other upon said pulley, said cables being anchored at fixed points independently of said reciprocating head, one of said cables operating as the head moves in one direction to impart rotative movement in one direction to the cam and cam shaft and the other cable being effective as the head moves in an opposite direction to impart an opposite rotative movement to the cam and cam shaft.
2. In a heel compressing machine, the combination with a reciprocating head, of a slotted rest block carried by said head, a mold removable with respect to said rest block, all the parts of said mold being integral, a pressure member positioned for movement relative to the mold, a cam shaft journaled in the rest block, a rotative cam on said shaft and operable within the slot of the rest block, said pressure member having a depending post which contacts directly with said cam, and means operable by the movement of said head for imparting rotative movement to the cam shaft and said cam.
3. In a heel-compressing machine, the combination with a vertically-movable head, a mold carried thereby, and a pressure member occupying a stationary position, of a second pressure member positioned within the mold, a cam movable with said head and mold and co-operating with said second pressure member, a cam-shaft provided with a pulley, and chains coiled oppositely on said pulley and anchored so as to impart rotative movement to said pulley upon the rise and fall of said head, said cam shaft and cam controlling the position of said second pressure member so that it cooperates with the first pressure member in compressing a heel and said second pressure member is so positioned that it supports a compressed heel in the path of an incoming heel in order to eject the former.
4. In a heel compressing machine, the combination with a vertically movable head, and a mold carried thereby, of a supporting member attached to said head for movement therewith, a feed slide supported on said member for reciprocating movement relative to said mold, a drop weight for moving said feed slide in one direction, and means operated by the rise of said head for imparting movement in an opposite direction to said feed slide.
5. In a heel compressing machine, the combination with a vertically movable head, and a mold carried thereby, of a supporting member attached to said head for movement therewith, a feed slide supported on said member for reciprocating movement relative to said mold, means for moving the feed slide in one direction, a slide-actuating

member mounted on said head for movement therewith, an operative connection between said slide actuating member and the machine frame for imparting movement to the slide-actuating member by the rise of the head, and a connection between the feed slide and the slide-actuating member for positively moving said feed slide in one direction.

6. In a heel compressing machine, the combination with a vertically movable head, and a mold carried thereby, of a supporting member attached to said head for movement therewith, a feed slide supported on said member for reciprocating movement relative to said mold, means for moving the feed slide in one direction, a slide-actuating pulley rotatably mounted on said head, and a plurality of chains wound oppositely on said pulley, one of said chains being anchored at a fixed point and the other chain being connected to the feed slide whereby movement in an opposite direction is imparted to said feed slide upon the rise of said head.

7. In a heel compressing machine, the combination with a reciprocating head, of a slotted rest block carried thereby, a mold, an apertured distance block intervening the rest block and the mold, a pressure member positioned for movement within the mold, said pressure member being provided with a depending post which is slidable in the distance block, a cam shaft journaled in the rest block, a cam carried by said cam shaft, said cam being operable within the slot of the rest block and having engagement with the post of said pressure member, and means controllable by the movement of said head for imparting rotative movement to the cam shaft and the cam.

8. In a heel compressing machine, the combination with a reciprocating head, of a mold all the walls of which are in fixed invariable relation to each other, said mold being carried by said head, a pressure member positioned within said mold to form the bottom thereof, said pressure member being provided with a depending post, a rotative cam mounted in said head, said cam being in direct contact with said post for imparting movement to the pressure member, and means operated by the reciprocating movement of the head for imparting rotative movement to said cam.

9. In a heel compressing machine, the combination with a reciprocating head, of a mold all the walls of which are in fixed invariable relation to each other, said mold being carried by said head, a pressure member positioned within said mold to form the bottom thereof, said pressure member being provided with a depending post, a shaft mounted in said head, a rotative cam on said shaft, said rotative cam being in

5 direct contact with said depending post for imparting movement to the pressure member relative to said mold, an operating member on said cam-shaft, and means controllable by the reciprocating movement of the head for shifting the operating member so as to impart rotative movement to said cam.

10. In a heel compressing machine, the combination with a reciprocating head, and 10 a mold thereon, of a heel blank guideway carried by said head and positioned in co-operative relation to said mold, said guideway operating to direct heel blanks into position to enter the mold, a feeder reciprocal relative to the heel blank guideway for moving heel blanks toward the mold, and means dependent upon the movement of said head for imparting movement to said feeder.

20 11. In a heel compressing machine, the

combination with a reciprocating head, and a mold thereon, of a heel blank guideway carried by said head and positioned in co-operative relation to said mold, said guideway operating to direct heel blanks into position to enter the mold, a feed member reciprocal relative to the heel blank guideway, means separate from said head for moving the feed member in one direction, and means operated by the movement of the head for imparting positive movement in an opposite direction to said feed member.

In testimony whereof, I have hereunto set my hand this fourteenth day of September, 1914.

HOWARD V. HILL.
